UNITED STATES PATENT OFFICE

DONALD V. POWELL, OF CHICAGO, ILLINOIS

SPARK PLUG

Application filed May 20, 1927. Serial No. 192,959.

My invention relates to that general class of devices known as spark plugs for use wherever found applicable. The invention has among its objects the production of a 5 spark plug of the kind described that is simple, durable, efficient and satisfactory for use wherever found applicable. The invention has particularly among its objects the production of a spark plug that is substantially self-cleaning, which will not easily foul 10 and which will deliver a particularly hot effective spark and ignite the charge in a most satisfactory manner. Many other objects and advantages of the construction herein 15 shown and described will be obvious to those skilled in the art from the disclosure herein given.

To this end my invention consists in the novel construction, arrangement and combination of parts herein shown and described, 20 and more particularly pointed out in the claims.

In the drawings, wherein like reference 25 characters indicate like or corresponding parts:

Fig. 1 is a top view of my improved spark plug;

Fig. 2 is a partial sectional view through 30 the same, the core being shown in elevation;

Fig. 3 is a view in elevation of the inner 35 end of the plug; and

Fig. 4 is a sectional view taken substantially on line 4—4 of Fig. 2.

Referring to the drawings, wherein I have 35 illustrated the preferred embodiment of the invention, the numeral 1 indicates the metal body portion of the spark plug having a screw-threaded part 2 adapted for engagement with the usual spark plug opening in 40 an internal combustion engine, the part below the threaded portion being slightly reduced in diameter as shown at 3 and formed with a smooth exterior surface.

Fitting into the body 1 and held in place 45 by means of the nut 4 is the usual porcelain member 5 carrying the electrode 6. The lower end of the electrode 6 projects slightly below the lower end of the porcelain and the lower end of the porcelain is preferably 50 formed with a tapered portion 7 which is dis-

posed in a chamber 8 in the body portion 1. The lower end of this chamber, in the preferred form, is formed with an inclined or tapered wall 9, the lower end of which communicates with a substantially Venturi passage 10. Arranged within the body 1, preferably the externally threaded portion thereof, is an annular flange 11 having an inner tapering wall forming a wall of said passage 10, thus forming a substantially Venturi passage 55 between the chamber 8 and the outer chamber 12 in the reduced part of the plug. 60

A second electrode 14 is arranged in opposed relation with the electrode 6 and as shown, is carried by a conical member 15 which may be supported within the chamber 12 by means of a cross bar or web portion 16. This cross bar 16 is positioned within the outer end of the reduced portion 3 against a shoulder 17 and the outer end of the reduced 70 portion 3 is turned inwardly around its edges as shown at 18 for retaining the bar 16 in place.

It will be noted that by having the flange 75 11 extended downwardly into the chamber 12, the outer inclined wall thereof together with the wall of the chamber forms an annular recess 19 which serves as a trap for catching the oils entering the chamber 12 upon opposite sides of the bar 16. In order that 80 the oils will be directed toward this annular recess 19, the lower side of the conical member 15 is formed with an outwardly inclined wall 20 which, it will be noted, will direct the oils toward the wall of the chamber 12 causing them to travel upwardly into the recess 19 and prevent them passing through the passage 10 into the explosive chamber 8. 85

At the upper end of the porcelain 5 and connected with the electrode 6 is the usual connection 21 for the electric circuit. Extending through from opposite sides of the threaded portion 2 of the body are the openings 22 which communicate with the chamber 8 and are arranged substantially in line with the meeting ends of the electrodes 6 and 14 so that the points of the electrodes are visible through these openings. This is preferable should it be desired to inspect the electrodes or to adjust the electrodes 14 as by inserting 90 140

a gasket or washer between the shoulder 17 and the bar 16, for instance, during the manufacture.

It will be apparent from the foregoing that the particular structure set forth forms a combustion chamber 8 for receiving gases under compression, which when ignited will expand and the ignited gases be discharged at high velocity through the Venturi passage leading to the outer chamber 12 and thence into the compression chamber of the engine cylinder, igniting the gases therein by a volume of burning gases. This action can be best understood when considering the relative proportional pressures that take place during this action. The gas compression which, at 60 pounds per square inch in both the engine cylinder and the compression chamber 8, when ignited instantaneously, causes an increased compression of the gases in the chamber 8. Thus, the rapid expansion of the gas under restricted surroundings causes them to be discharged at high velocity through the passage 10 and chamber 12 into the engine cylinder. From this, it will be apparent that with the rapid discharge of the gases outward through the passage 10 and the chamber 12, it will create a suction to return the oils on the wall of chamber 12 and entrapped in the annular recess 19 into the engine cylinder and at the same time have a tendency to clean the chamber 12 of any oil or carbon so as to keep this chamber in a comparatively clean condition at all times. It will be noted, in the preferred form, that by reason of the Venturi passage between the chambers 8 and 12, the velocity will be increased, as they are discharged from the chamber 8 to the cylinder. The size of the passage between the portion 11 and the cone 15 may, of course, be made as desired, either by varying the proportions of the parts or by adjusting the cone-shaped member outwardly or inwardly. The cone-shaped holder 15 for the electrode 14 serves two principal purposes—First—in the restriction of the gases on discharge from the chamber 8 serving to increase the velocity of the gases escaping from this chamber through and into the combustion chamber of the engine through the chamber 12. Second—it prevents the admission of oil or loose carbons from entering the chamber 8 as it will be observed that the cone, at its widest points is wider than that of the passage 10. Thus, the oils striking the inclined or tapering surfaces 20 will be directed toward the inner wall of the chamber 12 and trapped in the annular recess 19 to be thrown back outward at the next explosion. It will be apparent that the inclined wall portions of the flange 11 are disposed at an angle that assures that the most rapid movement of the gases from its downward discharge and serves as an oil trap in forming the annular

recess 19, the gases being compressed through the passage 10 into the chamber 8.

In the plug shown, the electrode 6 is adjustably mounted in the porcelain 5 so that the distance or space between electrodes or points may be varied as desired. As shown, a bushing 25 is mounted in the porcelain which is preferably molded around the same, the bushing being internally threaded to receive the threaded outer end of the electrode 6. The porcelain is provided with an opening or bore 26 of a size to receive the electrode but not so as to bind, thereby permitting easy adjustment of the parts. The upper end of the plug 25 is preferably cupped or recessed as shown at 27 to receive a packing 28 of asbestos or any other suitable form of gasket, 29 being a lock nut to compress the gasket and lock the electrode in place.

The porcelain is shown provided with a cap 30 which is held in place by the nut 21, thumb nut 31 being provided at the extreme end of the electrode 6. By removing the nut 21 and cap 30, the nut 29 may be loosened and the electrode then adjusted to separate the points or bring them closer together, as desired. The adjustment, as mentioned before, may be easily noted through the sight opening 22 which normally is closed by the side walls of the spark plug opening in the engine when the plug is seated. It will be apparent that the plug, as constructed, will operate at low temperature as the porcelain 5 is exposed only to the burning gases which are contained in the chamber 8 and the temperature is raised as the gases are forced through the passage 10 serving as the means of compressing or densifying the gases, the elevation of temperature being proportional to the density of the gas.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the class described and in combination, a body shell having a chamber with a restricted outlet, an internal offset in the body at one end of the chamber forming a flared mouth for said outlet, an electrode in the shell, a cone-shaped support having a portion positioned within said flared mouth, and a second electrode carried by said support and extending into said chamber with its end spaced from the end of the first electrode.

2. In a device of the class described and in combination, a body shell having a chamber with a restricted outlet, and a second chamber in line with the first chamber, an electrode

in the first chamber, and a second electrode supported in the second chamber and projecting into the first chamber in alignment with the first electrode.

5 3. In a spark plug, a body shell having a chamber, the wall of the chamber at its lower end being tapered inwardly to form a restricted outlet, an electrode carried by the shell and projecting into the chamber, said shell having a second chamber between the outlet and the end of the body shell, the shell provided in the second chamber adjacent said outlet with a pocket arranged to entrap oils and prevent the same from entering the first chamber, and a second electrode in the second chamber and extending through the restricted outlet.

10 4. In a spark plug, a body shell having a chamber, the wall of the chamber at its lower end being tapered inwardly to form a restricted outlet, an electrode carried by the shell and projecting into the chamber, a second chamber between the outlet and the end of the body shell, an internal annular offset having its lower edge tapering to form a venturi at the restricted outlet, and projecting into the second chamber to provide a pocket in the outer chamber and prevent oils from entering the first chamber, a cone-shaped

15 30 support in the second chamber, and an electrode carried by said support and extending through the outlet.

20 5. In a spark plug, a body shell having an inner chamber and an outer chamber with a restricted passage forming communication between said chambers, an internal annular offset in said shell providing a flared mouth for said opening and forming an annular oil pocket in the outer chamber, an electrode

25 40 extending into the inner chamber from one end of the shell, a conical support carried by the shell and extending into the flared mouth, and a second electrode carried by said support and having its inner end spaced from the inner end of the first electrode.

30 6. In a spark plug, a body member formed with an inner and outer chamber and a Venturi passage between said chambers, and a cone-shaped electrode support in the outer chamber projecting into said passage.

35 7. In a spark plug, a body member formed with an inner and outer chamber and a Venturi passage between said chambers, a depending annular flange around said passage having tapered walls, one of which walls with the inner wall of said outer chamber defines an annular pocket, and a cone-shaped electrode support in the outer chamber projecting into said passage.

40 8. In a spark plug, a body member formed with an inner and outer chamber and a Venturi passage between said chambers, a cone-shaped electrode support in the outer chamber projecting into said passage, and an annular inclined wall on the lower portion of

the cone-shaped member inclining in a direction opposite the inclination of the other surface of said member.

In testimony whereof, I have hereunto signed my name.
